UNITED STATES PATENT OFFICE.

FEERDINAND A. PFEIFFER, OF SPRINGFIELD, OHIO, ASSIGNEE TO THE THOMAS & ARM-
STRONG COMPANY, OF LONDON, OHIO, A CORPORATION OF OHIO.

TANK.

Application filed August 31, 1925. Serial No. 53,529.

This invention relates to tanks, such as stock tanks, and more particularly to a joint between the side walls and bottom plate of such a tank.

One object of the invention is to provide such a joint which will be absolutely leak proof and which will have sufficient mechanical strength to effectively prevent the separation of the connected parts.

A further object of the invention is to provide such a tank which will be simple in its construction and can be produced at a low cost.

Other objects of the invention will appear as the device is described in detail.

In the accompanying drawings Fig. 1 is a perspective view of a tank embodying my invention; Fig. 2 is a side elevation, partly broken away, of a portion of the joint; Fig. 3 is a transverse section taken through the joint on the line 3-3 of Fig. 2; Fig. 4 is a transverse section taken through the joint on the line 4-4 of Fig. 2; and Fig. 5 is a sectional detail view of portions of the dies for forming the joint.

In these drawings I have illustrated one embodiment of my invention and have shown the same as applied between the side walls and bottom plate of a stock tank but it will be understood that this particular embodiment has been chosen for the purposes of illustration only, and that not only may the joint take various forms but that it may be applied to tanks or similar structures of various kinds and between various walls thereof, the terms "side wall" and "bottom plate" being used herein as words of description and not as words of limitation.

The stock tank here illustrated is oblong in form and comprises a vertical wall 1, which may be characterized as the side wall of the tank, and a bottom plate 2 connected at its edges with the lower portions of the side wall. The side wall is provided along its lower edge with a channel which opens inwardly, that is, toward the interior of the tank, and the edge portions of the bottom plate extend into this channel. The channel may be formed in any suitable manner but preferably the lower portion of the side wall is first bent outwardly, at substantially right angles to the wall, as shown at 3, to form the top wall of the channel and the outer part of this outwardly bent portion is then bent

downwardly and inwardly, as shown at 4, 55 to form the bottom wall of the channel. The two walls of the channel are substantially parallel but are spaced some distance one from the other. If desired, the inner edge 60 of the bottom wall 4 may be bent upon itself, as shown at 5, to reinforce the channel and to avoid a raw edge on the bottom wall of the channel. A packing 6 of any suitable character is interposed between the bottom plate and the upper wall of the channel. 65 Preferably the bottom plate and packing are placed in position after the lower portion of the side wall has been bent outwardly and before the outer part of this portion of the wall has been bent inwardly to form the 70 bottom wall of the channel, thus enclosing the edge portion of the bottom plate in the channel. The upper and lower walls of the channel are pressed together to compress the packing between the top wall thereof and 75 the bottom plate and to tightly grip the bottom plate and thus form a tight joint. To provide a rigid connection between the bottom plate and the side wall of the tank, 80 the walls of the channel, the bottom plate and the packing are provided with alined indentations, as shown at 7 in Figs. 2 and 4, the indentations of the one part extending into the indentations in the adjacent part so that the several parts are brought into interlocking 85 relation and the side wall and bottom plate of the tank are held firmly against relative displacement. The indentations made of any suitable shape or size but I prefer that they shall be circular in form and of 90 small size, and shall be spaced apart along the channel, after the manner of rivets.

Any suitable means may be employed for forming the indentations and for compressing the walls of the channel and the packing 95 but I prefer to use for this purpose dies which will form the indentations at one point only and will compress the walls of the channel for a considerable distance on each side of the indentation, such dies being illustrated 100 in Fig. 5. In the operation of the dies the alined indentations of the several parts will be formed and the top and bottom walls of the channel compressed at the same operation and in forming a succeeding indentation 105 the dies are so placed that they will slightly overlap that portion of the channel which has been compressed in the forming of the

preceding indentations, thus causing the walls of the channel to be compressed throughout the length of the channel and providing an absolutely tight joint.

5 It will be obvious that in forming these joints I have entirely avoided the use of openings through the walls of the channel and bottom plate, such as are necessary for a riveted joint, and that as a result any leakage 10 which takes place must first pass about the packing 6, then between the bottom wall of the channel and the bottom plate and with these parts firmly compressed together such leakage is practically impossible. The parts 15 of the joint which are pressed into interlocking engagement serve to positively prevent any separation of the bottom plate and the side wall and to hold these parts rigidly in their proper relation one to the other. Not 20 only is this joint very strong and positively leak proof but it can also be produced at a cost much lower than the cost of the riveted joint and in much less time.

While I have shown and described one embodiment of my invention I wish it to be understood that I do not desire to be limited to

the details thereof as various modifications may occur to a person skilled in the art.

Having now fully described my invention, what I claim as new and desire to secure by Letters Patent, is:

In a structure of the character described, a side wall having its lower portion shaped to form an inwardly opening channel having substantially parallel upper and lower walls, 35 a bottom plate having an edge portion extending into said channel, and packing interposed between said bottom plate and the upper wall of said channel, the walls of said channel being pressed together throughout 40 the length thereof to compress the packing between the upper wall of said channel, said bottom plate and the walls of said channel and said bottom plate, said packing having relatively small aligned portions thereof 45 pressed upwardly at separated points along said channel to cause a projection on each lower member to extend into a recess in the adjacent upper member.

In testimony whereof, I affix my signature 50 hereto.

FERDINAND A. PFEIFER.
